(57) **CLAIM**

The ornamental design for a picture frame, as shown and described.

DESCRIPTION

FIG. 1 is a bottom and left perspective view of a picture frame showing my new design;

FIG. 2 is a top and right perspective view thereof;

FIG. 3 is a front view thereof;

FIG. 4 is a left side view thereof, the right side view being a mirror image; and,

FIG. 5 is a top view thereof, the bottom view being a mirror image.

The broken lines are for disclosure purposes only and do not form part of the claimed design. The back view does not form part of the claimed design.
